UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A BASE FOR LAMP-FOUNTS.

SPECIFICATION forming part of Design No. 24,135, dated March 19, 1895.

Application filed February 18, 1895. Serial No. 538,903. Term of patent 3½ years.

To all whom it may concern:

Be it known that I, ALBERT PATITZ, of Meriden, in the county of New Haven and State of Connecticut, have invented a new Design for a Base for Lamp-Founts, (Case D;) and I do hereby declare the following, when taken in connection with the accompanying drawings and the letters of reference marked thereon, to be a full, clear, and exact description of the same, and which said drawings constitute part of this specification, and represent, in—

Figure 1, a side view of a base for lamp-founts embodying my design; Fig. 2, a top view of the same.

15 This invention relates to a design for a base for a lamp-fount, and the design consists in the configuration and ornamentation as shown in the accompanying illustrations.

20 In general outline the base is circular, curving gradually upward and inward, having four legs A, terminating in upwardly turned scroll feet B. The surface of the legs is ornamented by floriated sprays C, springing from downwardly depending scrolls D, and meet-

ing at the center side as at E. These sprays 25 inclose a plain circular medallion F, surrounded by a ribbed scroll G. Above these medallions and meeting sprays is a circular rib H, from which springs a circular series of outwardly projecting scallops, above which 30 rises a circular band J, contracting toward the upper edge of the base, and ornamented by alternating plain medallions K, surrounded by a flat border L, and overlapping inverse scroll ornaments M, all as shown in 35 the accompanying illustrations.

I claim—

The design for a lamp-fount base as herein described and shown in the accompanying 40 illustrations.

In testimony whereof I have signed this specification in the presence of two subscribing witnesses.

ALBERT PATITZ.
